UNITED STATES PATENT OFFICE.

LOUIS A. MILLER, OF KANSAS CITY, MISSOURI.

PROTECTOR FOR CARBOYS.

1,159,698.

Specification of Letters Patent.

Patented Nov. 9, 1915.

Application filed October 15, 1914. Serial No. 866,837.

To all whom it may concern:

Be it known that I, LOUIS A. MILLER, a citizen of the United States, residing at Kansas City, in the county of Jackson and 5 State of Missouri, have invented certain new and useful Improvements in Protectors for Carboys, of which the following is a specification.

My invention relates to carboys for the 10 storage and shipping of acids, mineral waters, or other liquids, and has for its object the provision of a shield adapted to be so secured upon the casing surrounding the carboy as to protect the projecting neck of 15 the carboy against injury, prevent the displacement of the stopper, and also hold the carboy rigidly in place so as to prevent undue jarring or rattling in the casing should the packing be insufficient.

Another object is to provide a device of 20 this character which may be quickly and easily removed bodily from the carboy casing without damaging or marring the casing.

A further object of my invention is the 25 provision of means for firmly locking in position the means provided for holding the stopper in place.

Other objects and advantages, such as 30 extreme simplicity, efficiency, durability, cheapness, and the general improvement of the art will be more fully set forth in the following specification and illustrated in the accompanying drawings, in which like reference characters designate similar parts in 35 all of the views, and in which:

Figure 1 is a vertical sectional view 40 through a carboy casing, showing the protector applied thereto, Fig. 2 is a top plan view, Fig. 3 is a detail sectional view showing means for attaching the protector to the carboy casing, Fig. 4 is a similar view showing a different mode of attachment, Fig. 5 is a detail sectional view of the neck engaging 45 means; and Fig. 6 is a modification of the stem without a clamping block and with the lock nut in operative position; in this construction the stem contacts with the stopper.

Referring more particularly to the drawings the numeral 1 designates a carboy casing, which is formed in the usual manner and comprises a boxlike structure having its top provided with a circular aperture 2 55 through which is adapted to pass the neck 3 of a carboy 4 which is contained within

the casing 1 and may be spaced from the walls thereof by means of packing 5.

My improved protector is adapted to be secured upon the top of the casing 1 and 60 over the neck 3 of the carboy, as shown in Fig. 1. This protector comprises arms 6 which extend upwardly and are bent intermediate their ends to form horizontal portions 7 which cross each other preferably at 65 right angles. A screw-threaded aperture is formed through the intersecting portions 7 and is adapted to be engaged by a screw-threaded stem 8 which is provided upon its upper end with a preferably square head 9 which has its sides provided with openings 10 for a purpose to be described. Mounted 70 on the stem 8 intermediate of its head 9 and the intersecting portions 7 of the protector arms 6 is a threaded lock nut 11 which when screwed down firmly against the intersecting portions 7 will hold the stem 8 against upward or accidental movement. The stem 8 is also provided at its lower end with a reduced neck 12 and a head 13 which is disposed in a recess 14 formed in a clamping 75 block 15. This head 13 is prevented from withdrawal from the recess 14 by a plate 16 secured upon the block 15 and provided with a central aperture 17 of less diameter 80 than the head 13. It will be obvious that this plate must be of the ordinary split construction to allow it to be fitted around the neck 12. Upon the lower ends of the arms 85 6 are formed horizontal projections 18 having openings 19 through which they may be secured by bolts, screws, rods or like means to the top of the casing.

In securing the protector upon the casing 1, I preferably employ the means illustrated 95 in Figs. 1 and 3, which consists in securing a ring 20 upon the casing 1 by means of screws 21. This ring 20 is provided with a plurality of apertures 22 through which are adapted to be inserted bolts 23 having preferably square heads 24 disposed in recesses formed in the lower side of the ring 20, or the bolts may be swaged or riveted in place.

The application of the protector is as follows: The bolts 23 being inserted in the 105 ring 20 and the ring placed in its proper position the protector is set on the ring so that the openings 19 in the horizontal extensions 18 of the arms 6 will slip over the bolts 23, and the nuts 25 are then threaded 110 upon the bolts 23 and screwed down firmly upon the extensions 18, thus holding the

protector rigidly in place. The stem 8 is then rotated by engaging the head 9 with a wrench or other suitable article, or by inserting a nail or the like in one of the 5 openings 10 in the head 9, until the block 15 contacts firmly with stopper 3' on the end of the neck 3 of the carboy, when the lock nut 11 is screwed down on the portions 7 and the carboy held firmly within the casing, 10 and any movement of it, and the working loose of the stopper prevented. To simplify the attaching means, I may, if desired, use wood screws 29 instead of bolts 23 and have them pass through the openings 19 in the 15 extensions 18 and into the top of the casing 1, as illustrated in Fig. 4.

It will of course be readily understood that the protector may be of any desired shape other than that illustrated in Fig. 1. 20 It will also be noted that the provision of the ball and socket connection of the stem 8 with the block 15 allows the block to accommodate itself to any obliquity of the stopper or mouth of the carboy, and that the 25 lock nut 11 screwed down until it bears firmly against the intersecting portions 7 will prevent the stem working loose and thereby releasing the stopper or cork, or permitting it to become loosened.

Having thus described my invention what I claim is:

1. In combination with a carboy and its casing, a protector comprising upstanding arms crossing each other, a screw-threaded bolt carried by said arms for engaging the stopper of the carboy, and a lock nut on said bolt adapted to engage said arms and hold said bolt firmly when in contact with said stopper.

40 2. In combination with a carboy consisting of a bottle and its casing, a protector detachably mounted on said casing and comprising upstanding arms crossing each other and having a screw-threaded aperture at their point of intersection, a screw-threaded bolt in said aperture and a threaded lock nut on said bolt above said arms; said bolt being adapted to engage the stopper of said bottle, and said nut being adapted to hold said bolt against accidental displacement when in engagement with said stopper.

45 3. In combination with a carboy and its casing, a protector comprising arms and means for detachably securing said arms upon said casing, said means comprising horizontal extensions formed on said arms and provided with apertures, a ring secured upon said casing and provided with upstanding bolts, said apertures in said horizontal extensions being adapted to be engaged by said bolts, and means on said bolts for preventing the withdrawal of said extensions.

4. In combination with a carboy and its casing, a protector comprising upstanding arms crossing each other, screw-threaded means carried by said arms for engaging the top of the neck of the carboy, and means for detachably securing said means upon said casing, said means comprising a ring secured upon said casing and provided with upstanding projections adapted to project through openings formed in said arms, and means on said upstanding projections for clamping said arms upon said ring. 65 70 75

5. A carboy comprising a bottle and a casing having an opening in its top, a ring surrounding said opening and secured upon said casing, upstanding bolts secured in said ring, upstanding arms secured at their ends to said bolts, said arms crossing each other intermediate of their ends and having a screw-threaded aperture through their center at the point of intersection, a screw-threaded bolt mounted in said aperture, and a lock nut upon said bolt and adapted to engage said arms at their intersection. 80 85

6. In a carboy consisting of a bottle and casing, a protector comprising a ring secured to the casing, upstanding bolts secured in said ring, upstanding arms crossing each other and having apertures in their ends, said bolts extending through said apertures and having their ends protruding above said ends, means on the protruding ends of said bolts for securing said arms to said bolts, a screw-threaded bolt mounted in a screw-threaded aperture through said arms at their point of intersection, and a lock nut and a swivel block upon said last named bolt; said swivel block being adapted to engage said bottle. 90 95 100

7. In a carboy consisting of a bottle having a neck and a casing having a central opening in its top, a protector comprising a ring secured to said casing around said opening, inverted bolts having their heads secured in said ring, a bent arm extending over the top of the neck of the bottle and having apertures in its ends, said bolts extending through said apertures and protruding above said ends, means on said protruding ends for securing the ends of said arm to said bolts, a screw-threaded bolt mounted in a screw-threaded aperture in the center of said arm above the neck of the bottle, and a lock nut and a block on said screw-threaded bolt; said block being swiveled on the lower end thereof and adapted to engage the neck of the bottle. 105 110 115 120

In testimony whereof I hereto affix my signature in the presence of two witnesses.

LOUIS A. MILLER.
